SELF-LOCKING GARMENT HANGER

Sylvester Kreitmayer, Brooklyn, N. Y.

Application April 7, 1945, Serial No. 587,045

2 Claims. (Cl. 24—232)

1

This invention relates to an attachment for garment hangers, for locking the hooks of the hangers against accidental displacement from a supporting line or rod, and one of its objects is to provide a simple attachment, which may be easily attached to the garment hanger hook, and operated to lock the hook on a supporting line or rod, or to release the hook from the line or rod.

Another object of the invention is the provision of a safety lock for garment hanger hooks, which includes a U-shaped portion adapted to clutch the shank of a garment hanger hook, and another U-shaped portion or arm adapted to confine the supporting line or rod in the arch of the hanger hook, so that the hook cannot be accidentally displaced from the line or rod.

With the above and other objects in view, the invention consists in certain new and useful constructions, combinations, and arrangements of parts, clearly described in the following specification, and fully illustrated in the accompanying drawings, in which—

Fig. 1 is a side elevation, showing a conventional garment hanger supported on a clothes line, and also showing the attachment in locked relation to the hook of the garment hanger.

Fig. 2 is a side elevation of the garment hook and attachment, in locked relation thereto.

Fig. 3 is a vertical sectional view, taken on line 3—3 of Fig. 1, looking in the direction of the arrows.

Fig. 4 is a perspective view of the attachment removed from the hanger hook.

Referring to the accompanying drawings, which illustrate the practical embodiment of my invention, 5 designates a conventional garment hanger, which is provided with a conventional hook 6.

In the conventional use of the hanger the hook is mounted on a clothes line 7, or upon a rod or other horizontal support, and the garment which is hung on the hanger may be easily displaced from the supporting line or rod, by the action of the wind, when the garment is hung out in a yard or in the open air; or by careless handling when the garment is hung in a house or store.

To prevent accidental displacement of the hung garment from the supporting clothes line or rod, I provide an attachment 8, which includes a U-shaped clutch arm 9 and a U-shaped hook locking arm 10, which extends laterally of the clutch arm 9.

The U-shaped clutch arm 9 includes the side walls 11 and 12, and the connecting end wall 13. The side walls 11 and 12 are formed with arched

edges 11' and 12', which are bent slightly toward each other, so as to have a spring clutching action on the shank 6a of the garment hook. These side walls are also formed with outwardly directed finger lugs 14 and 15, located below the clutch edges 11' and 12', and which are adapted to be engaged by the finger or thumb of the user, so as to enable the user to forcibly displace the clutch jaws 11' and 12' from the shank of the hook.

The U-shaped locking arm 10 is provided with side walls 16 and 17, and a connecting end wall 18. This end wall is formed with openings 18a and 18b, through which the hook arch 6b may be threaded, in the manner illustrated in Fig. 3, thus permitting the free end portion 6' of the hook to project through the end wall 18 below the locking arm 10.

When the attachment is in locked relation to 20 the garment hanger hook, the locking arm 10 will extend across the hook arch 6b, thereby confining the clothes line or supporting rod 7 under the hook arch, which is closed thereby.

The lower end of the clutch arm 9 normally 25 engages the hanger 5, so that the attachment cannot slide downwardly on the hanger hook, and the releasing finger lugs 14 and 15 project laterally of the shank 6a of the hook a sufficient distance to develop the movement necessary to 30 disengage the clutch arm from the hook shank.

When the clutch arm is disengaged from the hook shank, the locking arm may be slidably disengaged from the arch of the hook, or swung around so that the outer end 10a of the locking 35 arm will be alone disengaged from the hook arch. This outer end is rounded, so that it will not bruise any garment it may engage.

When the arch 6b is extended from the arm 10, the end 6' of the arch at the opening 18b, becomes spaced outwardly from said arm, thereby 40 rendering the device readily removable from or attachable to a line 7 or the like. The initial step of assembly consists in entering the end 6' upwardly into the opening 18a, with the arch 6b transverse; then said end is moved circularly, and 45 downwardly through the opening 18b. During the circular movement the arch 6b is also moved into longitudinal relation with the arm 10.

Certain garment hooks are formed with offset 50 loops 19, and the clutch arm 9 may be formed with a single longitudinal opening 13a in the end wall 13 to receive this offset loop.

It is obvious that the attachment may be used 55 for locking garment hook hangers on outside or inside garment supporting rods or lines, and the

attachment may be used for supporting garments for display in stores, so that unauthorized persons cannot easily remove such hook hangers from their supports. The invention provides means for safely hanging garment hangers in closets, so that a hanger will not be displaced from its support and caused to fall upon a dusty floor, when another garment is removed from a hanger in the closet or wardrobe.

It is understood that various changes may be made in the details of construction, their combination and arrangement, and in the selection of materials required for the construction of the safety locking device.

Having described my invention, I claim as new:

1. A locking device for a garment hanger provided with a shank connected to a yoke and terminating above in an arcuate suspension hook, said locking device including a U-shaped channel member having opposed edge portions mutually deflected toward each other to produce a resilient clutching action on the shank when caused to clasp said shank, and a lateral U-shaped arm rigidly extending from the upper

portion of said channel member at an angle thereto, the U-shaped arm having openings spaced apart for receiving the arcuate hook therethrough to confine portions thereof within the same and expose an intermediate arched portion of the hook above said U-shaped arm when the opposed edge portions of the channel member clasp said shank.

2. A locking device for a garment hanger according to claim 1, in which the mutually deflected edge portions of the channel member have outwardly flaring lug portions.

SYLVESTER KREITMAYR.
